VIOLIN

George E. Van Pelt, Tucson, Ariz.

Application October 20, 1954, Serial No. 32,740

Term of patent 14 years

(Cl. D56—1)

Fig. 1

Fig. 2

Fig. 3

Fig. 4

Fig. 5

Fig. 6

Fig. 1 is a perspective view of a violin showing my new design;

Fig. 2 is a top plan view thereof with pegs, strings, bridge, tail piece, and chin rest, omitted for convenience of illustration;

Fig. 3 is a side elevational view thereof;

Fig. 4 is a bottom plan view thereof;

Fig. 5 is an end elevational view thereof;

Fig. 6 is an elevational view of the end opposite that shown in Fig. 5.

I claim:

The ornamental design for a violin, substantially as shown and described.
